Primary Examiner — Melanie H Tung
Assistant Examiner — Lavone D Tabor(57) **CLAIM**

The ornamental design for a head portion of an oral care implement, as shown and described.

DESCRIPTION

FIG. 1 is a right, front perspective view of a head portion of an oral care implement according to the new design;
FIG. 2 is a left, front perspective view thereof;
FIG. 3 is a left, rear perspective view thereof;
FIG. 4 is a right, rear perspective view thereof;
FIG. 5 is a front view thereof;
FIG. 6 is a rear view thereof;
FIG. 7 is a right side view thereof;
FIG. 8 is a left side view thereof;
FIG. 9 is a top view thereof; and
FIG. 10 is a bottom view thereof.

All broken lines shown in the drawings are for environmental purposes only and form no part of the claimed design.
